Hirosuke Horiuchi

UNITED STATES PATENT OFFICE.

HIROSUKE HORIUCHI, OF TAIWAN, JAPAN.

WATER-TUBE BOILER.

1,343,824.

Specification of Letters Patent. Patented June 15, 1920.

Application filed March 13, 1917. Serial No. 154,644.

To all whom it may concern:

Be it known that I, HIROSUKE HORIUCHI, a subject of the Empire of Japan, residing at 41, 2-chome, Tomongai, Taihokujonai, Taihokucho, Taiwan, Japan, have invented certain new and useful Improvements in Water-Tube Boilers, of which the following is a specification.

My invention relates to improvements in water-tube boilers, and consists in such a boiler having front and rear water boxes substantially vertically arranged near the ends of a horizontal steam drum and connected to the under side thereof, two sets of water-tubes inclining in opposite directions and connecting the water-boxes to form a V-shaped combustion chamber. A U-shaped feed-water heater is preferably located in such chamber. The invention has for its objects to render the circulation of water more active and the production of steam more rapid.

The annexed drawing shows a side view in vertical section of a water-tube boiler constructed according to my invention.

In the drawing, 1 is the main wall of the boiler, 2 the fire-grate, 3 the steam drum, 4 the front water-box, and 5 the rear water-box. 6 is a set of lower water-tubes, 7 a set of upper water-tubes, 8 a V-shaped combustion chamber, 9 a series of baffles, 10 a U-shaped feed-water heater and 11 a feed-water pipe.

The front water-box 4 and rear water-box 5 communicate with the steam drum 3 near its ends and are substantially vertically arranged as aforementioned. The lower water-tubes 6 connect the water-boxes at the lower parts thereof and are arranged at an angle of 8° to 13° to the water level, while the upper water-tubes 7 connect the water-boxes at the upper parts thereof and are arranged at an angle of 2° to 6° to the water level, the latter set of water tubes being inclined in the opposite direction to the former. The V-shaped combustion chamber 8 is formed between the two sets of water-tubes and the U-shaped feed-water heater 10, secured to the rear water-box 5, is located in said V-shaped chamber.

The lower water-tubes 6 lying immediately over the firegrate 2 are highly heated and as they are more steeply inclined than the upper water-tubes 7, the circulation of water is chiefly caused in them. The water therein enters the front water-box 4, ascends, and enters the upper water-tubes to reach their rear ends. The steam produced in the lower water-tubes, on entering the front water-box, separates itself from the water and ascends into the steam-drum 3.

Hot air is delivered into the V-shaped combustion chamber by means of any suitable device and perfect combustion is attained, so that the upper water-tubes are further heated, and then, as they are slightly inclined upwardly toward their rear ends and in as much as steam can not remain stagnant, evaporation vigorously sets in, and the steam thus produced, on entering the rear water-box 5, ascends to the steam drum 3.

The cooler water in the steam-drum 3 and the water not evaporated in the upper water-tubes will descend the rear water-box 5, and the cold water fed from the feed-water pipe 11, after it is warmed by the feed-water heater 10, will also descend the rear water-box 5. As both the front and rear water-boxes have large areas, the separation of steam from water is very effective, so that the circulation of water in the boiler is uniform and rapid through all its parts.

The combustion of fuel, as well the conduction of heat, is vigorous, and the circulation of water, on that account, is very effective, so that the steam is rapidly produced, and the water-tubes are not liable to obstructions. Further, as the construction of the boiler is very simple, a number of water-tubes may be effectively arranged in a comparatively small space, and consequently the output of the boiler increased.

What I claim is:—

The combination in a water tube boiler, of a horizontal steam drum, front and rear water-boxes substantially vertically arranged and having their upper ends communicating with the interior of said steam drum, upper and lower sets of water tubes connecting the water boxes and placing the same in commu-

nication, the upper set of tubes being inclined to the horizontal at an angle of greater than 2° in an upward direction toward the rear water-box, and the lower set of water-tubes being inclined to the horizontal at an angle of greater than 7° in a downward direction toward the rear water-box so as to form a V-shaped combustion chamber between said sets of tubes, and a

feed water heater connected to the rear wa- 10 ter box and extending into said V-shaped combustion chamber.

In testimony whereof I have affixed my signature in presence of two witnesses.

HIROSUKE HORIUCHI.
